UNITED STATES PATENT OFFICE.

ALBERT J. BIRKESTRAND, OF CAMBRIDGE, IOWA.

SHOVEL.

1,032,984.

Specification of Letters Patent. Patented July 16, 1912.

Application filed October 14, 1911. Serial No. 654,747.

To all whom it may concern:

Be it known that I, ALBERT J. BIRKESTRAND, a citizen of the United States, residing at Cambridge, in the county of Story 5 and State of Iowa, have invented certain new and useful Improvements in Shovels, of which the following is a specification, reference being had therein to the accompanying drawing.

10 This invention relates to cultivator shovels, and has for its object the production of a shovel of a reversible type wherein the blade may be changed to perform a function of the ordinary cultivator blade as 15 a gopher, or as a shovel.

Another object of this invention is the production of an efficient securing means for firmly attaching the blade of a cultivator to the frame thereof in both of its adjusted 20 positions.

With these and other objects in view, this invention consists of certain novel constructions, combinations, and arrangements of parts as will be hereinafter fully described and claimed.

In the drawings: Figure 1 is a perspective view of the device being used as a shovel blade. Fig. 2 is a detail perspective view of the cultivator blade detached from the 30 plow frame. Fig. 3 is a detail perspective of the cultivator blade in the position as used as a gopher. Fig. 4 is a plan view with the blade partly broken away.

Referring to the drawings by numerals 1 35 designates the blade engaging arm of the plow frame which arm fits into the socket plate 2 carried by the blade 3. The socket plate 2 is provided with a longitudinally extending channel and a transversely extending channel crossing said longitudinally extending channel intermediate its ends. The socket plate is also provided between the longitudinally extending channel and transversely extending opening at the 40 junction thereof with web portions 4, 10 and 12 for allowing a clamp 5 to be secured thereto. Each of the web portions is provided with an aperture 6 through which apertures pass the bolts 7 for firmly clamping the clamp 5 in engagement with the 45 socket plate 2.

When the device is used as a shovel blade the arm 2 is placed in the longitudinally extending channel 8 as illustrated in Fig. 1,

and the clamp 5 has its ends secured to the 55 web portions 4 and 10 for holding the blade firmly in engagement with the arm 1. When the device is used as a gopher, the arm 1 is placed within the transversely extending channel 11 and the clamp 5 engages the web 60 portions 4 and 12 of the socket plate, at the same time straddling the arm 1 for clamping the blade upon said arm. The blade 3 is sharpened upon its side as at 13 and terminates into a point at its end as at 14, the side 65 sharpened edge acting as the gopher and the pointed end acting as the ordinary shovel.

From the foregoing description, it will be obvious that a simple and efficient device 70 has been produced whereby the same blade may be used for two different purposes by easily and quickly changing the position of the blade upon the plow frame. Of course, the socket member may be welded or otherwise attached to the blade and it will be further obvious that the device may be readily attached to any frame desired, which is provided with depending arms so as to engage the socket plates 2. 75

What I claim is:—

1. A reversible blade for the cultivator consisting of a rectangular body having a pointed end and a sharpened side a socket plate carried by said blade having a longitudinally extending channel and a transversely extending channel, webs positioned between said channels at the junction thereof, said webs having apertures formed therein, a clamp engaging said webs and being adapted to be swung upon said webs for attaching said plate in an adjusted position to a support. 85

2. A cultivator blade of the class described comprising a socket plate having channels formed therein and extending at right angles to each other, webs positioned between said channels, a clamp engaging two of said webs and being adapted to be swung so as to engage another of said webs 90 whereby said blade may be supported in different adjusted positions. 100

In testimony whereof I hereunto affix my signature in presence of two witnesses.

ALBERT J. BIRKESTRAND.
